TRAFFIC SIGNAL AND TIMER

Alvin O. Olafson, St. Paul, Minn., assignor to
National Traffic Signal Company, St. Paul,
Minn., a corporation of Minnesota

Application May 27, 1931, Serial No. 540,223

2 Claims. (Cl. 177—337)

This invention relates to an automatic traffic signal and timer, wherein the same may be operated automatically by the traffic along the respective highways.

5 This signalling device is automatic in its operation, so that the vehicles traveling along the streets or highways will operate a suitable switch device or mechanism placed in the pavement or street so that when the vehicle travels over the same, the signal will be operated through a timing mechanism which controls the operation of the signals in order that traffic may pass at intersections in a regulated manner without confusion or traffic jams or long delays, which are undesirable. With this mechanism, the traffic may be regulated automatically so that busy highways may have preference over more seldomly used intersecting highways and yet the main or busy highway cannot hold up traffic indefinitely along the lesser used highway.

A feature of this automatic signalling device and timer resides in a mechanically operated timing mechanism which is provided with intermittent operating means adapted to be operated by the vehicles traveling along the highways or streets or by suitable switches which may be operated by pedestrians or by time clocks of a suitable nature. The timer mechanism may also be operated by suitable switch means which is operated by street cars, railways or like carriers. While automatic vehicle operating signals, using switch mechanism in the pavement or road have been used heretofore, my signal operating mechanism and timer is of a different character having a simple and positive nature, economical to manufacture and positive in operation so as not to be affected by the burning out of tubes or other radio operating mechanism. This is an important feature in my automatic signal operating means and timer and distinguishes the same from all other types of automatic vehicle operated signals used heretofore of which I am aware.

In this timer and switch mechanism for operating the signals, I provide a means of allotting certain periods of time which are readily adjustable for the highways in different directions so that one highway can have a period of longer time allotted to it than the other highways at the intersection, and by the intermittent operation of the means which operates the timing periods, each highway may be allotted a definite period of time for traffic to travel over the same before the signal can be taken away from that highway and unless traffic comes along the opposite

highway, the signal may remain to permit traffic to travel along either of the highways as long as the signal is set with the GO sign along a particular highway. All of this operating mechanism is mechanical but electrically propelled and after each period allotted, the timing mechanism comes to rest until again tripped for operation.

It is also a feature to provide an automatic signalling device with the timing mechanism which permits the pedestrians to operate the signal if it is desired. Means is provided so that after the signal has been operated by the pedestrian, a certain interval of signalling time must elapse before the same can be reoperated so that it is impossible to get a traffic jam even though the signal should be tampered with by children or those pedestrians who would not have consideration for the travel of traffic in any direction on the highways. Thus, I provide a signalling device which is automatic in regulating and adjusting itself so as to control traffic in a practical manner, whether operated by the vehicles of traffic, or by individual pedestrians, to regulate the signals at the intersection of highways.

The timing mechanism is an important feature of a signal operated automatically by the vehicles or the traffic, as well as where it is desirable to have the signal operated also by the pedestrians. While pedestrian operated signals are not as well known as other types of signals which are operated by timing mechanisms or automatically by the traffic, yet they have their important functions for certain intersections and they form a practical means of permitting school children to go over busy highways protected by the signal when set to permit them to cross. Such pedestrian operated signals of today with which I am familiar have defects which make them seriously objectionable and I believe that I have overcome these defects in this form of my timing mechanism and signalling device, which will be more fully pointed out hereinafter in the specification. A feature of my timer resides in a simple mechanism which is adapted to operate so that operating mechanism may be placed in the pavement of the highways which permits the vehicles to automatically operate the signalling mechanism through this timer. The timer is provided with means which permits the same to be set so that different intervals of time may elapse for different highways and a longer or shorter period may be provided for various highways at the intersections and yet devices placed in the pave-

ment will operate the timer to change the traffic signals through the timing mechanism. Further, the timer may be operated by a single pair of switching or operating mechanisms for the same in one highway, while the other intersecting highway, which would be termed the main highway with the heaviest traffic, would under all ordinary circumstances have the free right-of-way and would not require operating switches for the timer of the signal. In this form of my timer a simpler structure with fewer parts is used. The timer operating in this manner would be operated to change the signals at the intersections only at a time when traffic would come along the lesser traveled highway, and within a certain period after the vehicle had come to the intersection the timer would cause the signal at the intersection to be changed to permit the traffic on the lesser highway to pass over the main highway. With this form of my timer, after the time allotted for the traffic to pass across on to the main highway has elapsed, my timer automatically again sets the signal for travel along the main highway.

There are many advantages in this simple form of timing mechanism to automatically control vehicle traffic, as well as pedestrian traffic, and wherein a mechanism is provided which cannot easily get out of order and which is simple in operation, positive in timing the intervals between the changes of the traffic signals controlled by the timer, and wherein a timing mechanism is provided which may easily be set to change the same to operate in various ways to control the traffic at intersections. These will be more fully pointed out.

The timer mechanism for regulating the interval of time of operation of traffic signals is of the character and nature as disclosed in my Patent No. 2,026,648 granted January 7, 1936 on application Serial No. 292,834 filed July 14, 1928, and in my application Serial No. 477,510 filed Aug. 25, 1930.

In the drawings forming a part of the specification:

Figure 1 illustrates diagrammatically a street intersection showing the position of the street contacts and signal.

Figure 2 illustrates a front view of my timer with the front lowered.

Figure 3 illustrates diagrammatically a side view of my timer casing showing the hinge mechanism.

Figure 4 is a sectional detail on the lines 4—4 of Figure 2.

Figure 5 is a section on the lines 5—5 of Figure 2, the timer having been removed from the casing.

Figure 6 is a front view of the timer mechanism.

Figure 7 is a side elevation view of the timer mechanism.

Figure 8 is a rear view of the timer mechanism.

Figure 9 illustrates diagrammatically a detail of the circuit closing switch operation.

Figure 10 illustrates diagrammatically one position of the motor circuit switch in operation.

Figure 11 illustrates diagrammatically a different position of the switch shown in Figure 10.

Figure 12 illustrates diagrammatically a plan view of the motor circuit operating switches.

Figure 13 illustrates the contact switch means for operating the traffic signal.

Figure 14 is a wiring diagram for my timer.

Figure 15 is a wiring diagram for my timer when but two of the street contact pads are used.

The timer A may be placed in any suitable position near the street intersection B illustrated in Figure 1, and is adapted to be controlled by contacts C and D set into the surface of the street and operated by the weight of automobile wheels bearing on the surface of the same to control the traffic signal E. By the term timer, I mean to designate the mechanical apparatus for changing the signals, and which is electrically operated, particularly when traffic actuated or when set to operate continuously. The timer A is set into a casing 10 which forms a closure for the same and protects the timer mechanism against the weather. The casing 10 is formed with side walls 11, a rear wall 12 and a top 13. The front wall 14 forms the door through which access to the timer A is provided. The front wall 14 is equipped with angle members 15 on either side thereof which overlap the side walls 10 when the wall is in closed position to form a tight closure for the casing 10. The front wall closure 14 is pivoted at 16 to a pair of links 17 which in turn are pivotally connected to links 18. The links 18 are pivoted to the side walls 10 of the casing. The door in open position is illustrated in Figure 3, a lug 19 on the inner surface of the front wall 14 bearing against the front edge of the timer and holding the wall 14 in the horizontal position illustrated in this figure. In closed position, the wall closure 14 assumes the dotted position illustrated in Figure 3, one extremity of the wall 14 extending beneath the top 13 of the casing. A suitable stop 20 limits the movement of the links 17 and 18.

To enable the operator of the timer to have access to all sides of the timer mechanism, I support the timer mechanism upon a slidable plate 22 within the casing 10. The plate 22 bears upon the upwardly extending flange 23 of the bottom 24 of the casing and is provided with bearings 25 slidable upon rods 26 mounted horizontally in the bottom portion of the casing 10. The plate 22 and the timer mounted thereon may be pulled virtually entirely out of the casing 10, at all times being held firmly by means of the bearings 25.

The timer A is secured directly to an auxiliary plate 26 which is parallel to and spaced slightly above the plate 22 and secured upon the shaft 27. The plate 26 may be pivoted with relation to the plate 22 as illustrated in Figure 5 of the drawings, turning upon the shaft 27. A spring catch 28 on the plate 22 is provided with a hole 29 adapted to fit a pin 30 on the plate 26 to hold the plate 26 in proper relationship to the plate 22 at all times, except when access to the rear of the timer mechanism is desired. A base plate 26' spaced from the plate 26 by spacing studs 26'', provides a base to which the timer mechanism is secured.

The timer A is operated by means of an electric motor 32 which drives a series of reduction gears within the transmission housing 33. The reduction gearing operates a shaft 34 which extends from the housing 33. A gear 35 is slidably secured against turning upon the shaft 34 and is adapted to engage gear teeth or pins 36 mounted on the rear of the timing disk 37. The pins 37 are arranged in concentric circles forming a series of concentric pin gears so that by sliding the gear 35

35 along the shaft 34, the gear 35 may engage with various of the circles of pins 36. As the gear 35 is driven at a constant speed by means of the motor 32 and the reduction gearing, and as there are necessarily a different number of pins 36 in each of the concentric circles, the disk 37 may be driven at any one of a number of desired speeds by changing the position of the gear 35. The position of the gear 35 and the circle of teeth or pins 36 with which this gear engages, is tabulated by means of an indicator 38 on the front of the timer A, which indicator is pivoted to a plate 38' which is horizontally slidably on the shaft 41 and which engages a collar integral with the gear 35 to hold the gear in adjusted position. The indicator 38 may be set in any of the notches 39 to regulate the position of the gear 35 and to provide the desired speed for the disks 37 in accordance with the time interval desired which is listed upon the indicator plate 40. The period of time necessary for making one rotation of the disk 37 may thus be determined by placing the indicator 38 in the proper notch 39.

In order to divide the period of time of each rotation of the disk 37, to allow various lengths of time the traffic signal E displays a certain color along a certain street, I provide a pointer 42 which may be adjusted circumferentially along the surface of the disk 37. For the purpose of simplicity, I have provided a series of letters or other indicia 43 on the surface of the disk and the end 44 of the pointer 42 may be adjusted to point to any one of the letters 43. The pointer 42 is held in adjusted position by means of a pin 45 operated by a spring handle 46 normally extending into one of the notches 47 along the periphery of the disk 37. The notches 47 are disposed diametrically opposite the letters 43 on the disk 37 so that the pointer 42 may be held with the point 44 adjacent any of the letters 43. Means adjustable on this pointer 42 and means formed stationary on the disk 37 act to change the traffic signal E in a manner which will be hereinafter more clearly set forth, and because of the fact that the pointer 42 is circumferentially adjustable, the time of one revolution of the disk 37 may be divided into various proportions. For any time interval or combination of time intervals displayed upon the indicator plate 40, it is only necessary to place the indicator 38 in the notch 39 at the top of the column in which the desired combination is found, determining the time necessary for each revolution of the disk 37 and to place the pointer 42 pointing toward the letter indicated with the combination on the indicator plate 40 to divide the time of the revolution into the desired proportions.

My timer A operates to change the signal E at the proper intervals by operating a contact switch 49 which makes the contact, as illustrated in the wiring diagram in Figure 14 to the signal lights 50 and 51 from the electrical supply line. The contact 58 is operated between the terminal points 52 and 53 by means of a pin 54 mounted upon a slidable plate 55 within the angularly adjustable switch supporting plate 56. The plate 55 is slidable between pins 57 on the plate 56. A spring contact arm 58 is mounted through an insulation block 59 to the upwardly extending flange 60 formed along one side of the plate 56 and integral therewith. The spring contact arm 58 is provided with a hump 62 against which the pin 54 strikes as the plate 55 is moved into the dotted position illustrated in Figure 13. The spring of the arm 58 holds the same normally in contact with the

terminal 53 when the arm 58 is not contacting with the pin 54. However, when the plate 55 is moved into the dotted position illustrated in Figure 13, the pin 54 bears against the hump 62 and forces the contact arm 58 into contact with the terminal 52. The contact arm 58 is electrically connected with the terminal 63.

In order that the plate 55 may slide easily with reference to the plate 56, rollers 64 and 65 are provided secured to the plate 55 and the flange 60 respectively. The roller 64 bears against the flange 60 and the roller 65 bears against the plate 55 when this plate is moved longitudinally to the plate 56 causing the same to slide easily thereupon.

The plate 55 is moved longitudinally to the plate 56 to connect the arm 58 alternately with the terminal 52 and then the terminal 53. The plate 55 is moved longitudinally by means mounted upon the disk 37 which strike pins 66 and 67 secured to the plate 55. As the disk 37 rotates, wedge-shaped flange means, which will be described in detail later in the application, engage the pin 66 and the pin 67 alternately, forcing the plate 55 from the position illustrated in Figure 13 to the dotted position shown therein and return, electrically connecting the terminal 63 alternately with the terminals 52 and 53 to successively display STOP and GO lights 50 and 51 along each street of the intersection B.

The plate 56 is pivotally supported to the shaft 68 of the disk 37 by means of an arm 69 bent upwardly from the projecting flange 70 on the plate 56 and the inturned flange 72 integral with and extending upwardly from the flange 60, as illustrated in Figure 7 of the drawings. The flange 72 and the arm 69 merely rotate upon the shaft 68 so that the plate 56 is angularly adjustable about the periphery of the disk 37 and is spaced slightly therefrom, as illustrated in Figure 6.

In order that the traffic signal E may be operated only when traffic is passing the intersection B, the contact pads C and D are set into the surface of the pavement in such a manner that a circuit through the pads C and D will be closed by the weight of an automobile passing toward the intersection B over one of these pads. The timer A is arranged to operate the signal E to permit any car passing over one of the pads C or D to receive a GO signal. As contact is made in the pad D, a circuit is closed to the solenoid 73. The solenoid 73 drives the pin 74 upwardly against the arm 75 which is pivoted at 76. The arm 75 is illustrated in detail in Figures 10 and 11. A metal contact arm 77 is secured to the arm 75 and moves upwardly integrally with the arm 75. The pointer 42 is provided at one end with a wedge-shaped flange 78 outwardly projecting from the plane of the disk 37. This wedge-shaped flange 78 engages with the insulated end 79 of the contact arm 77 when the arm 75 is in the downward position illustrated in Figure 11, but the insulated end 79 when in the raised position of Figure 10 will not be engaged by the flange 78, the flange 78 passing beneath the same. The path of the flange 78 is illustrated at 80 in Figures 10 and 11 to better illustrate how the end 79 of the arm 77 is engaged by the wedge-shaped flange 78 as the disk 37 rotates. Once during each rotation of the disk 37, the contact arm 77 is forced downwardly by a lug 81 mounted upon the surface of the disk 37, and unless the circuit through the contact pad is completed subsequently, the end 79 will be forced outwardly. When

the wedge-shaped flange engages the insulated end 79 of the contact arm 77, the circuit is broken between the arm 77 and a contact finger 82 mounted adjacent the arm 77. It may be seen in Figure 14, that the circuit from the electrical supply line to the timer motor passes through the contact arms 77 and the contact finger 82. Accordingly, when the insulated end 79 is forced outwardly by the flange 78, the timer motor 32 will cease operating. The contact 77 is held in either raised or lowered position by means of an insulated spring 83 (Figure 11) secured to the base plate 26' and bearing against the same, in both positions, providing a friction retarding any change of position of this contact.

When the signal E displays a STOP light along the street F and a car passes over the contact pad D, a circuit is closed to the solenoid 73. This raises the arm 75 and the contact arm 77. If the wedge-shaped flange 78 is holding this arm 77 away from its contact finger 82, the operation of the solenoid 73 will raise the end 79 out of contact with this flange 78 closing the circuit between the arms 77 and the finger 82 and starting the motor 32 as shown in the wiring diagram of Fig. 15. The wedge-shaped flange 78 will then bear against the upwardly projecting pin 66 on the plate 55 and will slide this plate 55 into the dotted position illustrated in Figure 13, thus changing the signal E to display a GO signal along the street F. If, however, the disk 37 is in motion subsequent to the downward actuation by the lug 81, pad D is passed over, causing an impulse to raise the contact arm 77, the raising of the end of the contact arm 77 will place this insulated end 79 out of the path of the flange 78 so that the circuit between the arm 77 and the finger 82 will not be broken by the flange 78, and the motor 32 will continue to rotate the disk normally. Likewise, if a car passes over one of the contact pads C on the street G as the signal E displays a STOP signal for this street, a contact will be made to the solenoid 85 which raises an arm 88 which is integrally connected 45 with the arm 87 similar to the arm 75 to which a contact arm 88 is secured. The contact arm 88 is identical with the contact arm 77 and operates in the same manner. The arm 88 is provided with an insulated end 89 and normally 50 forms contact with the finger 90. The end 89 of the arm 88 is forced downwardly by the inwardly extending lug 92 formed on the end of the arm 42 which is radially adjustable from the center of the disk 37. The circuit between 55 the arm 88 and the finger 90 is broken by means of the wedge-shaped flange 94 formed on the periphery of the disk 37.

When the signal E displays a GO signal along one of the streets G or F, cars passing along this street may pass the intersection without delay as long as no car approaches at right angles. A car approaching along the street G when the GO signal is displayed along the street F, will operate the solenoid 85 to raise the contact arm 88. If the disk 37 has come to rest after previous actuations, and the flange 94 has forced the end 89 of the contact arm 88 out of engagement with the finger 90 to break the circuit, the raising of the arm 88 will immediately make contact between the arm 88 and the finger 90, starting the motor 32. The flange 94 will then bear against the pin 66 on the plate 55 sliding the plate from the dotted position in Figure 13 to the position illustrated in full lines, thus forcing the spring 75 arm 58 of the switch 49 into contact with the

terminal 53 and causing the signal E to display a GO signal along the street G after a short period. If the disk 37 has not had sufficient time after previous actuations to rotate to break the circuit between the arm 38 and the finger 90, the 5 arm 88 will be raised and the flange 94 in its rotation upon the disk will pass beneath this end 89, thus allowing the motor 32 to continue to rotate the disk 37. If no car approaches along the street F, the disk 37 will continue to rotate, 10 the pin 92 forcing the arm 88 downwardly into the path of the flange 94 so that when the disk rotates sufficiently, the flange 94 will bear against the end 89 of the arm 88 breaking the motor circuit and leaving the signal E displaying a GO 15 signal along the street G.

In the circuit illustrated in Figure 14, one of the line wires 105 is connected to the terminal 103, to the switch element 58, to one contact of each of the pads C and D, and to the switch arm 20 88. The vehicle actuation pad and operating solenoid circuits are formed by current passing through this line wire to the pads C and D. Current flows from the pads C, when the pad switch is closed, to the solenoid 85, through this solenoid 25 and to the other line wire 105. Current flows from the pads D, when the switch means therein is closed, to the solenoid 73, through this solenoid, and to said other line wire 105.

The motor circuits in Figure 14 extend from 30 said one line wire 105, through the arm 88, through the contact 90 to the switch 101, where the current is transmitted to the central terminal on one side of the switch, and to the motor 32. From the motor 32, the circuit extends to the 35 other central terminal of the switch 101, through the switch blade and to the arm 82. From this arm, the circuit extends through the contact arm 77, which is electrically connected to said other line wire 105.

The signal circuit extends from said one line wire to the switch element 58. The circuit extends either through the terminal 52 to one set of lights 50, or through the other terminal 53 to the other set of lights 51. Both sets of lights 50 45 and 51 are electrically connected with said other line wire.

When the switch 101 is moved into contact with terminals 103 and 104, it may be seen that it will direct current from the line wires 105 directly to the central switch terminals connected to the motor 32, to drive the motor continuously.

In the circuit shown in Figure 15, one circuit extends from one line wire (the left hand one in Figure 15), to the switch 101, both to the terminal 103 and to a terminal at the other end of the switch. Current passes through the switch blade in the switch position shown to the central switch terminal which is connected to the motor 32. Passing through the motor 32, the circuit extends 60 to the other central switch terminal of switch 101, through the switch blade to the contact 90. Circuit extends through the arm 88 and to the other line wire 105. This said one line wire is also connected to the pads C, and a circuit is provided through these pads when the switches therein are closed (in either pad) to the solenoid 85 which is connected to said other line wire. Said one line wire is also connected to the switch element 58, through which current flows to either 70 terminal 52 or 53, and to either the lights 50 or the lights 51, respectively. These lights are connected to said other line wire 105.

As has been stated after the timer disk has revolved sufficiently to break the motor circuit 75

and stop the motor, a car approaching on a cross street will change the signal after a short period. For example, when cars approach along the streets F and G simultaneously, after the signal 5 E has displayed a GO signal on the street G for a period of time, the car crossing the pad D will tend to change the signal E after a short interval and this interval must be sufficient to allow the car crossing a pad C simultaneously to pass the 10 intersection before the signal is changed. Otherwise, the car on the street G would be stopped between the pad D and the intersection B and the signal would not change back automatically to allow it to pass. This interval may be regulated 15 in a simple manner as will be hereinafter set forth in detail.

The contact arms 77 and 88 are oppositely disposed on either side of the disk 37. The lug 81 is mounted on the face of the disk 37 extending 20 outwardly from this disk at a point directly opposite the inward projecting flange 94 but somewhat closer to the center of the disk. This lug 81 which forces the arm 77 down into the path of the flange 78 is thus positioned directly above the 25 insulated end 79 of the arm 77 when the disk 37 ceases to rotate, the circuit being broken between the arm 88 and the finger 80. Therefore, as long as the disk remains in this position, the arm 79 is prevented from being elevated by the 30 solenoid 73 and successive cars passing over the pads on the street displaying the GO signal will not elevate the arm 77. This will prevent the signal E from returning to display GO after the disk starts to rotate because of cars driving over 35 the pads during the period the signal displayed GO and after the timer motor had stopped. Thus, cars crossing the pad D while the signal E displays GO along the street F, will not act to raise the arm 77, as this arm is held down by the 40 lug 81.

The lug 92 is mounted on the end of the arm 42 and extends inwardly from the disk 37. This places the lug 92 opposite the flange 78 so that as the flange 78 acts against the insulated end 45 79 of the arm 77 to break the contact between the arms 77 and the finger 82, the pin 92 will be positioned directly above the arm 88 and will stay in this position as long as the disk 37 is motionless, preventing the arm 88 from being 50 elevated. Thus, cars passing over the pad C when the signal E displays GO along the street G, will not raise the arm 88 as the pin 92 prevents such raising. The disk 37, pointer 42 and flanges 78 and 94 comprise the timer member.

55 I provide a means of insuring a proper interval between the time the car passing over the pads C or D on the street displaying a STOP signal while the motor of the timer is stopped, and the change of the signal E, to allow cars passing over 60 the pads on the street displaying the GO signal to pass the intersection. If this interval is not sufficient, cars on the street displaying the GO signal would likely become stranded between the pads and the intersection. It may be seen that a 65 short interval of time will elapse between the raising of one or the other of the arms 77 or 88 to start the timer motor and the time the flange 78 or 94 acts to change the spring arm 58 of the contact switch 49 to a different position. When 70 the gear 35 is in engagement with the outermost row of teeth 36, the disk 37 moves slowly and the interval provided is sufficient. If the plate 56 were not circumferentially adjustable about the periphery of the disk 37, increasing the speed 75 of the disk 37 would decrease the interval of time

between the raising of the arms 77 or 88 to start the motor of the timer and the changing of the signal E, because of the faster rotation of the disk 37. Means must be provided to keep the interval between the "making" of the contact to 5 start the timer motor and the changing of the signal E virtually constant. This is accomplished by means of regulating the adjustment of the plate 56 about the shaft 68. As has been pointed out the plate 56 is pivotally supported 10 on the shaft 68 by means of the arm 69 and the flange 72. This angularly adjustable plate 56 is secured to the plate 28 by means of an arm 96. The arm 96 is provided with a bifurcated end 97 between which the pin 98 secured to the arm 69 15 may operate. When the plate 38' is in the position illustrated in full lines in Figure 8, the plate 56 bearing the switch 49 is comparatively near the arms 77 and 88. Accordingly, the flanges 78 or 94 need not travel far in order to change the 20 signal E after the disk begins to rotate. However, when the plate 38' is in the position illustrated in full lines, the rotation of the disk 37 is very slow and accordingly, sufficient time is permitted, after the beginning of the rotation of the 25 disk to allow cars on the street displaying the GO signal between the pads and the intersection to cross the intersection before the signal changes. When the plate 38' is moved into the dotted position illustrated in Figure 8, the plate 30 56 is angularly adjusted by means of the arm 96 to cause the flanges 78 or 94 to travel a much greater circumferential distance between the time the disk 37 begins to rotate and the changing 35 of the signal. It may be seen, however, that when the plate 38' is in the dotted position the disk 37 travels at a much greater speed. Therefore, the interval between the start of rotation of the disk 37 and the changing of the signal E will remain practically constant regardless of 40 the speed of rotation of the disk 37, insuring a sufficient interval after the timer motor has started to allow cars between the pads and the intersection on the street displaying the GO signal to pass the intersection before the signal will 45 change.

My signal timer A is suited for virtually every condition of traffic, and will operate successfully under practically every possible situation. Cars on one street may travel continuously until a 50 car approaches in the other direction. If the cars on the first street have had their proper interval, the signal will change. If they have not had their proper interval, the signal will not change until this interval is elapsed. If a car 55 is waiting to cross the intersection, the signal will change back after a predetermined interval to allow it to pass. If no car is waiting, the signal will remain on the second street until changed by a car approaching on the first street. 60 If cars approach rapidly or continuously on both streets, the signal will change intermittently, allowing predetermined intervals of time on each street, which intervals may be regulated as desired.

65 It is sometimes beneficial to have the signal operable by pedestrians, to stop traffic to allow these pedestrians to cross the street. Contact buttons on each street wired in parallel with the contacts in the pads of that street may be provided, as illustrated at 100 in Figure 1 of the drawings.

70 For intersections having a lot of traffic along one street only, it is possible to construct the timer omitting one of the solenoids, one of the 75

contact arms, and one of the contact fingers. The timer constructed in this manner will operate to break the motor circuit only when the GO signal is in one direction, and after allowing 5 an interval on the cross street will automatically return to the busy street. A wiring diagram of this signal timer is illustrated in Figure 15 of the drawings.

The switch 101 is mounted on the rear of the 10 timer, and controls the circuit to the timer motor. When the switch is in the position illustrated in Figures 14 and 15, the timer is controlled by the pads C and D. When, however, it is desired to operate the timer mechanically to change the 15 signal E at regular intervals constantly, the switch handle 102 may be operated to throw the switch into the other position contacting the terminals 103 and 104. This connects the motor 32 directly to the supply line 105, so that the motor 20 operates continuously.

In accordance with the patent statutes, I have described the principles of operation of my traffic signal and timer and while I have endeavored 25 to set forth the best embodiment thereof, I desire to have it understood that this is only illustrative of a means of carrying out my invention and that obvious changes may be made within the scope of the following claims without departing 30 from the spirit of the invention.

I claim:

1. In combination with a traffic signal unit having stop and go signals for at least two interfering traffic lanes, a traffic actuated device 35 for each lane, an electric motor including a shaft, a circuit for energizing said motor including a pair of switches in series, one for each lane; means for displaying a go signal to any one lane while displaying a stop signal to a second 40 lane, said motor circuit, in the absence of traffic in said lanes having the said switch for the lane with the stop signal normally open, and the other closed; means for each lane operated by actuation 45 of a said traffic actuated device for the corresponding lane when it has the stop signal for closing said open switch whereby said motor circuit is closed; means operated by rotation of said shaft to change the display of said signals to give a go signal to the lane of the said actuated device and stop to the other lane, and means operated by rotation of said shaft a predetermined time after said change of signals, to open said other switch whereby the motor circuit is opened 50

and may be closed by an actuation of the other of said traffic devices on the lane now having the stop signal.

2. In combination with a traffic signal unit having stop and go signals for at least two interfering traffic lanes, a traffic actuated device for one lane, a second traffic actuated device for a second lane; an electric motor including a shaft, a circuit for energizing said motor including a pair of switches in series, one for each lane, a disk mounted on said shaft for rotation therewith, a first and a second cam device for corresponding lanes of said lanes mounted on said disk in circumferentially spaced relation and projecting therefrom; a first means for operating one of said switches including a cam member movable into two positions, one in the path of one of said cam devices to be engaged therewith and the other out of it, said first means maintaining its corresponding switch closed except when said one cam member is in the said one position and is engaged by said cam device in which case the said one switch is opened and the motor circuit open, a second means for operating the second of said switches including a second cam member movable into two positions, one in the path of the second cam device to be engaged therewith and the other out of it, said second means maintaining its corresponding switch closed except when said second cam member is in said one position and is engaged by said cam device in which case the said one switch is opened and the motor circuit open, said cam devices and cam members cooperating so that only one corresponding pair may be engaged at one time, a traffic actuated mechanism for each lane; means for displaying a go signal to a lane whose cam device and cam member are engaged, means operated by actuation of the traffic actuated device for another lane to move said last mentioned cam member out of the path of the last mentioned cam device whereby the motor circuit is closed, means operated by the resulting energization of said motor to display the go signal to said other lane, and operating with cooperation of said disk and cam devices a predetermined time after the beginning of each display to bring a different cam member and cam device into engagement to open said motor circuit and to restore the moved cam member back into the path of its corresponding cam device.

ALVIN O. OLAFSON.
